UNITED STATES PATENT OFFICE

RICHARD H. NELSON, OF MOLINE, ILLINOIS, ASSIGNOR TO THE HERMAN NELSON CORPORATION, OF MOLINE, ILLINOIS, A CORPORATION OF ILLINOIS

RADIATOR

Application filed April 4, 1931. Serial No. 527,773.

This invention relates to tubular radiators which are provided with sheet metal fins to radiate the heat from the steam in the tubes to the air passing between the extended surfaces afforded by the heating plates.

In radiators of this type, it is customary to provide a group of tubes extending between manifolds, and make rigid connections at each end of the tubes with the adjacent manifold, with the result that the unequal expansion and contraction to which the individual tubes are subjected frequently subjects the radiator to strains which, in the course of time, cause leakage or otherwise injure the tubes by tending to open the pores of the metal which accelerates corrosion. It is therefore of the utmost importance that each of the tubes of a group, which are united at each end to a common header, should be permitted to expand and contract independently, since in this way only can provision be made for taking up the unequal strains to which the various tubes of the group are subjected.

The present invention relates to the provision in each tube of a bellows-folded, or similarly configured section, which affords opportunity for expansion and contraction without in any way materially complicating the structure and without impairing the integrity of the unions between the ends of the tubes and the headers.

The invention also relates to the combination of tubes thus formed with rigid headers united by the provision of rigid exterior connections, so that provision is afforded within a structure which is rigidly reinforced against deformation, for the individual expansion and contraction of the tubes without imparting such movements to the exterior configuration of the radiator structure as a whole. This arrangement enables the tubes and fins to be constructed of relatively thin and fragile material, in order to secure the maximum radiating effect and to reduce the weight of the material to a minimum, without, however, impairing the rigidity and ruggedness of the radiator as a whole, so that the latter may be readily shipped and ma-

nipulated and subjected to rough usage without impairment.

In previous structures with which I am familiar, attempt has been made to overcome the effects of unequal expansion and contraction by increasing the strength of the structure, but this has merely delayed the development of leaks and ruptures which ultimately occur, and at the same time increases the cost of production without securing actual relief from the difficulty.

From the standpoint of radiation, the use of a group of tubes with headers is preferable to the use of a single tube, since the group arrangement enables the radiator to be constructed to more desirable dimensions and multiplies the conduits for the travel of the steam, and otherwise improves the construction. A reduction in the number of tubes to one or two, compels the heat to travel longer distances from the core or heat source, and this extra heat travel requires more feet of surface at a lower temperature to get the same result. Heretofore, the merits of the desirable group arrangement of tubes with headers have been recognized, but the difficulties occasioned by unequal expansion and contraction have impaired the utility of the desirable group arrangement and have in a large measure deterred its use.

The present invention is intended to overcome the difficulties noted and to enable the light-weight tubes to be arranged in any desirable form of grouping without danger of development of strains or leaks and with ample provision for the reinforcement of the radiator group as a whole.

Further objects and details of the invention will appear from the detailed description thereof, in conjunction with the accompanying drawing, wherein:

Fig. 1 shows a radiator composed of a group of three tubes with a multiplicity of fins through which the tubes extend; and

Fig. 2 is a longitudinal sectional view taken on the line 2-2 of Fig. 1.

Each of the tubes 10 extends longitudinally of the radiator structure and has its ends brazed or otherwise rigidly secured within a tube plate 11 which is brazed or otherwise

rigidly united to a header 12. A similar arrangement is employed at each end of the radiator, and in view of the fact that the headers themselves form no portion of the present invention it is not deemed necessary to describe them in detail except to point out that they are preferably of a rugged cast construction and adapted to constitute the end reinforcements of the radiator structure.

- 10 In order to protect the more fragile tubes and fins, the respective headers are rigidly united by means of spacer bars 13 on opposite sides of the radiator, which bars are secured by screws 14 to the respective headers.
- 15 This affords an exterior cage construction which provides the necessary rigidity to prevent deformation and enables the radiating portions of the radiator to be formed of thin metal having high thermal conductivity
- 20 without requirement that the said radiating portions shall in themselves possess the strength required to support the radiator itself.

In order to provide for the individual expansion and contraction of the respective tubes, each of the tubes, near one of its ends, has formed therein the bellows-folded section 15 which extends for a short distance at a point in close proximity to the point of connection of the contiguous tube plate 11. It is not necessary to provide a similar bellows-folded section at the opposite end of the tube, nor is it essential that said section be located at one end of the tube, although for most purposes this will be found to be the most desirable location.

The group of tubes have mounted thereon a multiplicity of spaced fins or plates 16 which lie in closely adjacent parallel relation, and will ordinarily be of rectangular outline to give to the radiator structure, as a whole, a rectangular configuration. The fins are provided with aligned apertures through which the tubes extend, and the metal surrounding each of the apertures is displaced to form a circular flange 17, which arrangement serves to afford a close metal-to-metal contact between the fins and the tubes, and at the same time serves to space the fins to the desired distance from one another. It will be observed that each fin abuts closely against the edges of the flanges struck out from the next adjacent fin, so that the equal spacing of the fins is maintained from end to end of the radiator.

While the valves embodied in the headers in the particular form shown, constitute no portion of the present invention, nevertheless these valves may be briefly described as follows:

The inlet header at the left hand portion of the figures has located therein a valve member 18 which coacts with the annular valve seat 19 constituting the throat of an inlet port 20. The valve is carried by a stem 21

which extends exteriorly of the header and is provided with a bevel pinion 22 meshing with a bevel pinion 23 on a shaft 24 entered through a journal 25 and having at its outer end an adjusting handle 26, by which the valve may be regulated from a convenient point to admit a heating medium to the interior of the header.

The header, at the discharge end, is provided with a tapered valve 27 which seats within a nipple 28 controlling the flow of heating medium through the discharge port 29. The valve is thermostatically controlled by an expandible member 30, the upper end of which is secured to a cap 31 threaded through the upper wall of the header. These details may be varied or modified, or other forms of valve mechanism employed, without affecting the present invention, which resides primarily in the formation and mounting of the individual expandible tubes within a rigid framework capable of withstanding deformation.

The tubes are preferably formed of copper or other ductile metal having a high thermal conductivity, although the invention is not limited to tubes formed of any particular material. Nevertheless, the provision of bellows-folded sections enables very thin tubing to be employed, which not only facilitates the formation of the bellows-folded sections, but also improves the radiating properties of the tubing and reduces the cost of the material employed and the aggregate weight of the radiator as a whole. Furthermore, the arrangement is one which in no way impairs the rigidity of the connection between the tubes and headers which are secured in the usual manner, and constitutes a feature which may be provided at small cost and at the same time furnishes abundant provision for individual expansion and contraction without imposing appreciable strains upon either the tubing or the connections.

A simple and convenient method of forming the bellows-folded sections is by the employment of an exterior die having the proper configuration in conjunction with hydraulic pressure within the tube, which serves to distend the metal to the required degree to furnish the folded formation.

In view of the fact that the actual expansion and contraction of the tubing is but a fraction of the capacity of the bellows-fold to accommodate such expansions and contractions, it is obvious that the strains attending such expansion and contraction will be distributed and disseminated in such a way as to relieve the tube and connections from appreciable strains.

The provision of the reinforcing bars which connect the headers affords to the structure, as a whole, sufficient rigidity to prevent deformation due to the strains occasioned by the making of pipe connections.

or rough handling, so that the radiator, as a whole, will be protected against racking or deformation.

Although I have described the expandible and contractible section as being of bellows-folded form, it will be understood that by that expression I do not mean to limit the formation to precisely the configuration shown, since under that term I mean to include other equivalent configurations consisting of one or more bends in the pipe adapted to subserve the intended function and provide an area fitted to take up the expansion and contraction of the tubes under variations in temperature.

It is also obvious that round or square fin plates and spiral ribbon may be used on each tube as radiating surface.

I claim:

1. In a radiator, the combination of a pair of spaced headers, rigid reinforcing bars rigidly connected with the headers, a plurality of relatively thin and fragile radiator tubes having their ends rigidly secured within the headers, and a plurality of closely spaced radiating fins mounted upon the tubes, each of the tubes being provided with a folded section integrally formed with the tubes and adapted to provide for thermal expansion and contraction.

2. In a radiator, the combination of a pair of spaced headers, rigid reinforcing bars rigidly connected with the headers, a plurality of relatively thin and fragile radiator tubes having their ends rigidly secured within the headers, and a plurality of closely spaced radiating fins mounted upon the tubes, each of the tubes being provided with a bellows-folded section integrally formed with the tubes and adapted to provide for thermal expansion and contraction.

3. In a radiator, the combination of a pair of relatively shallow rectangular boxlike headers having flat ends, rigid reinforcing bars having their ends rigidly secured to the flat ends of the headers and constituting a cagelike structure, a plurality of relatively thin and fragile radiator tubes having their ends rigidly secured within the headers, and formed to provide for individual expansion and contraction within the rigid cagelike structure, and a plurality of closely spaced radiating fins mounted upon the tubes and lying between the rigid reinforcing bars.

4. In a radiator, the combination of a pair of relatively shallow rectangular boxlike headers having flat ends, rigid reinforcing bars having their ends rigidly secured to the flat ends of the headers and constituting a rigid cage-like structure, a plurality of relatively thin and fragile radiator tubes having their ends rigidly secured within the headers and extending in parallel relation with the rigid reinforcing bars and between said bars, each of the tubes being provided

with a bellows folded section integrally formed with the tube and adapted to provide for independent thermal expansion and contraction of each of the tubes within the cage-like structure, and a plurality of closely spaced fragile radiating fins mounted upon the tubes and lying between and in position to be protected by the rigid reinforcing bars.
